CLAIM

The ornamental design for an analyte sensor device, as shown and described.

DESCRIPTION

FIG. 1 is a top perspective view of an analyte sensor device showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a bottom perspective view thereof;

FIG. 9 is an exploded bottom perspective view thereof; showing the adhesive removed for clarity of illustration; and,

FIG. 10 is an exploded bottom plan view thereof, showing the adhesive positioned to the side for clarity of illustration. The evenly dashed broken lines in the figures showing an adhesive illustrate environment that forms no part of the claimed design. The remaining evenly dashed broken lines in the figures illustrate portions of the analyte sensor device that form no part of the claimed design.
